UNITED STATES PATENT OFFICE.

HOWARD D. COLMAN, OF ROCKFORD, ILLINOIS, ASSIGNOR TO BARBER-COLMAN COMPANY, OF ROCKFORD, ILLINOIS, A CORPORATION OF ILLINOIS.

MACHINE FOR OPERATING UPON WARPS.

Application filed April 18, 1919. Serial No. 291,061.

To all whom it may concern:

Be it known that I, HOWARD D. COLMAN, a citizen of the United States, residing at Rockford, in the county of Winnebago and 5 State of Illinois, have invented certain new and useful Improvements in Machines for Operating upon Warps, of which the following is a specification.

This invention relates to improvements in 10 warp-drawing and other machines for operating upon warps. Among the salient objects of the invention are to provide for an adjustment of the position of the thread-selecting mechanism to enable said mechanism to select threads, and to transport 15 threads selected by said adjustable mechanism to a point where they can be taken by the needle or other element intended to receive them.

20 In the accompanying drawings, Figure 1 is a fragmental front elevation of a warp-drawing machine embodying the features of my invention, a portion only of the warp-supporting frame being shown and the harnesses being omitted from the harness and 25 reed frame. Fig. 2 is a fragmental sectional view taken in the plane of dotted line 2-2 of Fig. 1. Fig. 3 is a fragmental vertical sectional view taken approximately in 30 the plane of dotted line 3-3 of Fig. 1. Fig. 4 is a fragmental plan view of the harness and reed carriage and adjacent parts. Fig. 5 is a fragmental front elevation of the main carriage and its supporting 35 means, showing also portions of the harness and reed frame and the warp frame. Fig. 6 is a fragmental end elevation of the machine as viewed from the left hand side of Fig. 1. Fig. 7 is a fragmental view 40 showing the reed, the reed hook and the thread-holding wheel in top plan view. Fig. 8 illustrates the operation of the needle and the reed hook. Fig. 9 is a fragmental top plan view of the machine. Fig. 10 45 is a fragmental horizontal sectional view illustrating a portion of the automatic throw-out mechanism controlled by the eye facer. Fig. 11 is a fragmental left-hand end elevation of the machine. Figs. 12 and 50 13 are views to illustrate the operation of transferring the thread from the needle to the reed hook, Fig. 12 being a view taken in the planes indicated by lines 12-12 in Figs. 8 and 13. Fig. 14 is a horizontal 55 sectional view illustrating a certain clutch.

Figs. 15 and 16 are views of portions of said clutch. Fig. 17 is a detail view of the means for operating the reed opener and feeder. Fig. 18 is a detail of the means for throwing into and out of operation the feed 60 for the main carriage. Fig. 19 is a front elevation of the thread-selecting, separating, severing and clamping mechanism, the means for transferring selected threads to the needle and the means for suspending 65 operation of the harness and reed handling mechanism while the thread-selecting mechanism continues to endeavor to take a thread. Fig. 20 is a fragmental front elevation of the mechanism shown in Fig. 19. 70 Fig. 21 is a section on line 21-21 of Fig. 20. Fig. 22 is a fragmental detail view of the warp-thread deflecting bar. Fig. 23 is a fragmental view of the thread-selecting and adjustment-controlling devices. 75

In the embodiment herein shown of the invention, the warp W, the harnesses H and the reed R are caused to travel past the operating mechanism. The warp, the harnesses and the reed are mounted upon a carriage 1. In the form selected for illustration the carriage 1 consists of two end brackets 2, two longitudinal bars 3 uniting the lower portions of the end brackets and a bar 4 (Fig. 2) joining the upper ends of 80 said brackets. The carriage 1 may be supported in the machine in any suitable manner; in the construction herein shown the lower ends of the end members 2 are provided with feet 5 that rest upon a guiding 85 and feeding member 6 rotatably mounted in the machine frame. The carriage 1 is further supported by means of rollers 7 mounted upon the bar 4 and running in a groove 8 formed in the upper edge of a rail 90 9. Said rail is rigidly secured in the machine frame.

The beam containing the warp to be drawn in may be supported in any suitable way, as, for example, in the manner shown 100 in my application Serial No. 557,859, filed April 27, 1910, (Patent No. 1,304,661, dated May 27, 1919) or it may be supported and fed in the manner described in Patent No. 1,190,245, granted July 4, 1916, upon an application filed by Burt A. Peterson. The portion of the warp to be acted upon by the machine may be held in any suitable way, as, for example, in a frame 10 (Fig. 2) 105 consisting of a plurality of yokes 11 rigidly se- 110

cured together by means including longitudinal bars 12. The upper portions of the yokes 11 are broken away in Fig. 1. At the upper ends of the yokes are two longitudinally extending thread clamps, the clamp 13 at the rear side of the frame 10 being fixed with relation to said frame, while the clamp 14 at the forward side of the frame 10 is pivotally connected with the yoke arms 10 in order that the clamp 14 may be moved away from the clamp 13 to place tension upon the threads held in said clamps. The clamps 13 and 14, the means for inserting threads therein, and the means for moving 15 the clamp 14 may be of any suitable character, as, for example, that fully disclosed in said Peterson patent.

Near the fixed clamp 13 is a longitudinally extending metallic bar 15 having a roughened upper edge (see Figs. 21, 22 and 23). The bar 15 is susceptible of being moved longitudinally for a slight distance, as explained in the Peterson patent, for the purpose of deflecting the threads laterally after 25 they have been clamped and tensioned. In passing from the warp beam to the clamps upon the warp carriage, the threads extend over a rod 16 (Fig. 3) loosely mounted in pockets 17 carried by brackets 18 fixed to 30 the bars 3. The threads extend behind a shield 19 secured to the frame 10. The frame 10 is removably supported upon the carriage 1 in any suitable manner, as by providing notches 20 in the upper edges of the brackets 18 to receive the bars 12.

The harnesses and the reed are supported in a frame 21 (Fig. 1) adapted to be removably mounted in the carriage 1. The frame 21 consists of two end members 22 10 rigidly united at their upper ends by means of two parallel rods 23. Projecting rearwardly from the end members 22 are two brackets 24 (Figs. 2 and 4). The rear ends of the brackets 24 are connected together by 15 a bar 25. A bar 26 extends from one end member 22 to the other and parallel with the bar 25. As shown in Fig. 3, the bar 26 is grooved to receive one of the bars of the reed R. The harness and reed frame 21 is 20 supported in the carriage 1 by means of arms 27 (Figs. 4 and 5) fixed to the end members 22 and having sockets 28 to receive the ends of one of the rods 23. Upon the bar 4 are mounted sockets 29 to receive the ends of the 25 other rod 23.

The harnesses herein shown are of ordinary construction, each consisting of an upper bar H' (Fig. 3), a lower bar H² and heddles H³, each heddle having an eye H⁴. 30 The harnesses are suspended from the rods 23 by suitable means such as hooks 30 like those fully illustrated and described in Patent No. 1,115,399 granted to me on October 27, 1914. Said hooks engage the upper 35 bars H' of the harnesses. The heddles are

held under control with the eyes lying in approximately the proper planes by means of two bars 31 and 32. The upper and lower portions of the bar 31 are beveled on opposite sides, and the upper portion of the bar 32 is likewise beveled on opposite sides to accommodate the crossing strands of the heddles. The ends of the heddle-controlling bars 31 and 32 are removably supported by the end members 22 in the manner described 70 in said Patent No. 1,115,399. Expansion spring devices 33 inserted between the bars 32 and H² place a slight tension upon the heddles H³. The bars 31 and 32 for each harness are inserted into the harness so that 80 one strand from the lower end of each heddle eye crosses a strand from an adjacent eye at a point between the bars 31 and 32. This arrangement places adjacent eyes at opposite sides of and slightly above the upper 85 bar 31.

The reed R is not secured to the harness and reed frame, but merely rests upon the bars 25 and 26.

The means for feeding the carriage 1 includes a shoe 34 (Fig. 1) attached to an arm 35 which is pivoted at 36 to the carriage 1. Rigid with the arm 35 is an arm 37 having an elongated opening in which is mounted an eccentric 38 (Fig. 18) pivotally mounted 90 upon the carriage 1. 39 is a hand lever fixed to the eccentric. The guiding and feeding element 6 is screw-threaded for a portion of its length, and the shoe 34 is threaded to engage said screw. By means of the hand 100 lever 39 the shoe 34 may be moved into and out of engagement with the screw-threaded portion of the member 6.

The means for rotating the feeding element 6 comprises a spur gear wheel 40 105 mounted upon one end of said element and meshing with a pinion 41 on one end of a shaft 42 (Fig. 3). On the opposite end of the shaft 42 is a spur gear wheel 43 that meshes with a gear wheel 44 (Fig. 6). The 110 gear wheel 44 is rotatably mounted in the machine frame and is rigidly connected to a beveled gear wheel 45 that meshes with a bevel pinion 46 fixed to the lower end of a shaft 47. On the upper end of the shaft 115 47 is a bevel pinion 48 that meshes with a similar pinion 49. The pinion 49 is rotatably mounted upon the drive shaft 50. Said shaft carries a tight and a loose pulley 51 and 52, respectively (Fig. 5). The pinion 120 49 is operatively connected to the shaft 50 by suitable means, as, for example, the clutch shown in Fig. 14. Said clutch comprises a flanged member 53 which is rigidly connected to the pinion 49. Keyed to the shaft 50 125 is a clutch member 54 carrying a clutch pin 55 (Fig. 15) which is normally projected beyond the periphery of the clutch member 54 by means of an expansion spring 56. The clutch member 53 carries a projection 130

57, which is arranged to be engaged by the clutch pin 55. A clutch-operating member 58 is pivotally supported in a bracket 59 (Fig. 9) attached to the machine frame. The member 58 comprises an annular flange adapted to surround a portion of the member 54, said flange having a cam portion 60 (Fig. 16) which is adapted to be engaged by the clutch pin 55 to force said clutch pin radially inward and thus out of engagement with the projection 57. Normally the clutch-operating member 58 is in idle position. The means for swinging said member 58 into position to throw out the clutch will 10 be described hereinafter.

15 The thread-selecting and separating mechanism may be of any preferred type. That herein shown is similar to the construction fully disclosed in the Peterson patent, and comprises a selector 61 (Fig. 19) provided with a minute hook or barb near its forward end of a size suitable to hook or spear one of the warp threads of the size upon which the machine is being operated.

20 The selector is arranged to be reciprocated across the plane of the warp at a point close to the deflecting bar 15. A torsion spring 62 yieldingly moves the selector toward the foremost thread of the warp. When the selector lifts the thread from the deflecting bar 15, the thread springs into a straight line between the clamps 13 and 14, thus moving away from the body of the warp. The selector is mounted in the forward end of an arm 63 pivotally mounted in a bracket 64. The arm 63 is rocked by means of an eccentric 65 upon a shaft 66 (Fig. 9), motion being communicated from the eccentric to the lever 63 through a bar 67.

25 The selected thread is separated from the remaining threads by means comprising a curved plate 68 fixed to arms 69 (Fig. 3), said arms being secured to a shaft 70 pivotally mounted in a bracket 71. The operating edge of the plate 68 is beveled or inclined at an angle of about 30° with said shaft, as shown most clearly in Fig. 9. At its rear end the plate 68 is provided with a separator finger 72. The plate 68 is oscillated by means of a crank 73 fixed to the shaft 70, which crank is connected by a connecting rod 74 to a crank arm 75 on the shaft 66. To the forward end of the separator plate 68 and at one end of its beveled separating edge is fixed a shear blade 76 (Fig. 19) adapted to coact with a stationary shear blade 77 fixed to the bracket 71. As the separator plate 68 is oscillated, the finger 72 enters between the selected thread and the body of warp threads, and the plate, following said finger, separates the selected thread from the adjacent threads substantially throughout its length between the clamps 13 and 14. When the operating edge of the plate 68 has passed the selected thread, the

latter has been raised from the body of warp threads so that it is cut between the two shear blades 76 and 77 as they come together. To clamp the thread before it is severed in order that it shall not jump or 70 become slack at the rear end of the separator plate, I provide an arm 78 pivotally mounted upon the shaft 70 and arranged to clamp the thread between itself and the outer end of the forward one of a number of stationary 75 fingers 79. A block 80 fixed to the arm 78 and having an inclined face raises the selected thread into proper position for clamping, if it has not already been so raised by the separator plate. A spring 81 tends to 80 move the arm 78 into clamping contact with the forward finger 79, and a pin 82 fixed in one of the arms 69 withdraws the arm 78 upon the return movement of the separator plate.

85 Directly behind the fingers 79 is a stationary plate or bar 83 having at its free end an inclined surface 84 up which the separated thread is pushed by a shoulder 85 on the separating finger 72. The incline 84 90 assists to raise the separated thread to the proper height to be taken by the transfer device hereinafter described.

95 The rate of movement imparted to the main carriage 1 by means of the screw 6 is proportioned as closely as conveniently practicable to the sley of the harnesses. Such proportioning may be effected in any suitable way, as, for example, by the use of change gears connecting the screw 6 to the 100 shaft 42, the gears 40 and 41 (Fig. 6) being typical of such change gears.

105 Inasmuch as the warp is somewhat wider than the harnesses, the movement imparted to the warp by the screw 6 is not quite sufficient to maintain a supply of threads within the range of action of the selector 61. I therefore, provide means for adjusting the position of the thread-selecting and separating mechanism from time to time as required 110 to keep the selector sufficiently close to the unselected threads. Referring to Fig. 19: The brackets 64 and 71 which support the selecting and separating mechanism are fixed to a slide 86 which is mounted for 115 movement parallel with the direction of movement of the carriage 1 upon a guide 87 (Fig. 2) in the machine frame. The shaft 66 is carried in bearings upon a bracket 88 (Fig. 9) fixed to the slide 86. Upon the rear end of the shaft 66 is a bevel gear 89 that meshes with a similar gear 90 which is splined upon the shaft 50. The gear wheel 90 has a hub or sleeve 91 which is rotatably mounted in a bearing 92 on the bracket 88, 120 the sleeve 91 being held against endwise movement with reference to the bearing 92 (see Fig. 14).

125 The means for moving the slide 86 upon its guide 87 comprises a rack 93 (Fig. 2) 130

fixed to the machine frame. Meshing with the rack 93 is a pinion 94 fixed to the upper end of a shaft 95 which is mounted in bearings on the slide 86. Fixed to the lower end of the shaft 95 is a bevel pinion 96 that meshes with a similar pinion 97 fixed to one end of a shaft 98. Said shaft is supported in a bracket 99 that is fixed to the bracket 64. On the other end of the shaft 98 is fixed a ratchet wheel 100 (Figs. 19 and 21). An arm 101 is pivotally supported upon the axis of the shaft 98 and carries a pawl 102 adapted to engage the ratchet wheel 100. Upon the upward movement of the selector lever 63, a finger 103 rigidly attached thereto engages a lug 104 on the hub of the arm 101 and thus moves said arm to give the pawl 102 a feed movement. A spring 105 restores the arm 101 and said pawl upon the downward movement of the selector lever 63. In order that the slide 86 shall not move through momentum, I provide a brake for the shaft 98 comprising a band 106 encircling a brake disk 107 fixed on said shaft. The band 106 is held from rotation by means of a pin 108 (Fig. 20) engaging lugs 109 on said band.

When the warp threads are in position to be engaged by the selector 61, the pawl 102 is prevented from causing movement of the slide 86. The means for thus controlling the slide-adjusting pawl comprises a lever 110 pivotally mounted at 111 on a bracket 112 fixed to the bracket 64. The upper portion of the lever 110 is curved to extend across the deflecting bar 15, and the end of the lever lies in the plane of the warp threads. A torsion spring 113 (Fig. 23) normally holds the lever 110 in contact with the foremost warp thread. Rigid with the lever 110 is an arm 114 (Fig. 19), the rear end of which is movable into and out of the path of a stud 115 on the arm 101. When warp threads are present at the selector 61 the end of the arm 114 lies in the path of the stud 115 and thus prevents the spring 105 from imparting a complete restoring movement to the arm 101 and pawl 102. When no thread is in position to be taken by the selector 61, or when the supply of threads accessible to the selector is reduced to a certain extent, the spring 113 will have raised the arm 114 so that said arm is out of the path of movement of the stud 115, whereupon the pawl 102 is enabled to impart one or more adjusting movements to the slide 86.

The means for positioning the heddles and facing the heddle eyes may be of any suitable character; herein is shown the same mechanism that is employed for that purpose in said Patent No. 1,115,399. In view of the fact that the heddle-positioning and eye-facing mechanism is fully disclosed in said patent it has been deemed unnecessary to illustrate it in detail herein. The eye-

pullers, the eye holders and the eye-detaining forks F are actuated by means of cams D², D³ and D⁷ respectively (Fig. 1), mounted on the shaft 42 in the manner described in said Patent No. 1,115,399.

Before starting a pair of harnesses through the machine it is necessary to separate the two sides of the heddle-positioning mechanism, and in order to accomplish this said mechanism is mounted on movable supports E² and E³ as explained in said Patent No. 1,115,399. The supports E² and E³ (Fig. 3) are mounted on rock shafts E and E' which are connected for synchronous movement by gear segments E⁴. The shafts E and E' are arranged to be rocked by means of a bell-crank lever fixed to one end of the rock shaft E. One arm E⁸ (Fig. 2) of this bell-crank lever is arranged to be moved by means of a hand lever E¹³ as explained in said patent. The arm E¹⁰ of the bell-crank lever carries a tooth E¹¹ adapted to enter a notch D²¹ in the periphery of a cam D¹³. The tooth E¹¹ normally lies almost in contact with the periphery of said cam, and therefore the throw-out mechanism can be actuated only when the notch and the tooth coincide, viz, when the needle and the heddle-handling mechanisms are in the proper position for the throwing out of said heddle-handling mechanism. The lever E¹⁰, the tooth E¹¹ and the notched disk D¹³ also constitute a safety device to prevent actuation of the machine while the heddle-handling mechanism is in thrown-out condition.

The eye-facer includes the two elements G⁶ and G⁷ (Figs. 3 and 10). The eye-facer is swung from one harness to the other by means of an arm G¹ and a connecting rod G extending from said arm to one arm of a bell-crank lever G³. The other arm of said bell-crank lever carries a roller that lies within the groove of the cam D¹¹ (Fig. 1).

The movement of one of the eye-facer jaws with relation to the other is caused by means fully described in said Patent No. 1,115,399, a portion only of said means being shown in the present drawings. Among the parts shown are the lever arms G¹³ and G¹⁵ (Fig. 9), the link G¹⁷ (Fig. 2), the bell-crank lever G¹⁶ and the cam disk D¹³.

Means may be provided for automatically stopping the entire machine if the eye-facer fails to grasp a heddle eye. This means may be of any suitable character; for example, the devices that sense the absence of a heddle eye may be like those fully disclosed in said Patent No. 1,115,399. The trigger lever G²⁰ shown in said patent is indicated in Figs. 3 and 10 of the present drawings. Said trigger lever engages a lever O⁴ which is fixed upon a shaft 116. A tension spring 117 tends to swing the lever O⁴ upwardly. Rigid with the shaft 116 is an arm 118. 119 is a latch pivoted at 120 and lying in the path of 130

movement of the arm 118. The latch 119 engages in a notch 121 formed in a belt shifter rod 122. The rod 122 carries a belt shifter fork 123. A tension spring 124 (Fig. 1) 5 tends to slide the rod 122 in the direction to shift the belt from the tight to the loose pulley. It will be seen that when the trigger lever G²⁹ is disengaged from the lever O⁴, the spring 117 will cause the latch 119 to be 10 withdrawn from the notch 121, whereupon the spring 124 will cause the drive belt to be shifted to the loose pulley 52. The rod 122 may be manually actuated to shift the belt to the tight pulley by means of a hand lever 125 (Figs. 2, 4 and 5), said lever being pivoted to the machine frame at 126 and having a suitable engagement at its rear end with the rod 122. The machine may be stopped at 15 will by pushing the hand rod 127 inward to disengage the latch 119 from the belt shifter rod. When restarting after such manual stoppage, the spring 119^a places the latch 119 in engagement with the belt shifter rod.

Preferably means is provided to arrest the 20 movement of the mechanism when the belt is automatically shifted as just described. This means may be of any suitable form, as, for example, that described in said Patent No. 1,115,399. In the present construction 25 there is an arm 128 (Figs. 3 and 10) that is rigid with the shaft 116. Said arm is connected by means of a link 129 to an arm 130 (Figs. 1 and 2) which is fixed upon a shaft 131. Rigid with the shaft 131 is a dashpot 30 N¹⁸. When the trigger lever G²⁹ releases the lever O⁴ to the action of the spring 117, the dashpot N¹⁸ is swung so as to place the plunger of the dashpot in the path of movement 35 of two diametrically opposite teeth D²² upon the cam D¹¹. The engagement of one of said teeth with the plunger causes the machine 40 to be yieldingly stopped.

Means is provided for manually actuating 45 the eye-facer to grasp a missed heddle. In order that this may be accomplished the cams D¹¹ and D¹³ which actuate the eye-facer are not secured directly to the cam shaft 42, but are fixed upon a sleeve (not herein shown) rotatably mounted upon the 50 cam shaft 42 and capable of being locked in engagement with said shaft by means of a dog D¹⁶ pivotally secured to the side of the cam D¹³ and adapted to engage a notch D¹⁷ in the periphery of a disk D¹⁸ fixed upon the shaft 42. The dog D¹⁶ is held in engagement with 55 the notch D¹⁷ by a spiral spring D¹⁹. Fixed with relation to the dog D¹⁶ is a lever D²⁰ provided at its ends with crank handles. In case the eye-facer fails to grasp a heddle 60 the machine stops, as hereinbefore described. The operator then reaches under the screw 6, grasps the crank handle which is within reach, operates said handle to withdraw the dog D¹⁶ from the notch D¹⁷, and by means of 65 said handles turns the cams D¹¹ and D¹³

through one revolution, thereby actuating the eye-facer to grasp the missed heddle. The operator then swings the dashpot N¹⁸ out of the path of the teeth D²², thereby causing the lever O⁴ to become engaged by the trigger 70 lever G²⁹. The machine is then restarted by swinging the hand lever 125 in the appropriate direction, the spring 119^a (Fig. 3) causing the latch 119 to move into the notch 121 to lock the belt shifter rod. 75

The means for drawing the selected threads through the heddle eyes and reed spaces may be of any preferred type. Herein is shown a needle 132 (Fig. 3) secured to an arm 133, said arm being fixed upon a rock shaft 134. 80 The shaft 134 is supported by bearings carried by machine frame. Rigid with the arm 133 is a gear segment 135 that meshes with a similar segment 136 fixed upon a rock shaft 137. Fixed to the shaft 137 is a gear segment 138 that meshes with a segment 139 which is pivotally mounted upon the shaft 134. Rigid with the segment 139 is an arm 140 having a roller stud that runs in the cam groove 141 of the cam D⁴. The cam D⁴ is 85 rigid with the shaft 42. As the cam D⁴ is rotated the arm 133 is oscillated to project the needle through a faced heddle eye and into position to receive a selected thread. In the continuing rotation of the cam D⁴ the 90 needle is retracted, thereby drawing the thread through the heddle eye.

Rigidly mounted in the machine frame is a block 142 (Fig. 8) located relatively close 100 to the path of movement of the harness eyes, said block having a guide opening 143 for the needle 132.

The needle 132 reciprocates in an invariable vertical plane. The thread-selecting and separating mechanism, however, is adjusted in position to compensate for localized irregularities in the spacing of the threads and the greater width of the warp as compared with the harnesses. In order to bring the selected threads to an invariable point where they can be taken by the needle 132, mechanism of any suitable nature may be employed. That herein shown comprises a transfer bar 144 (Fig. 19) mounted for substantially horizontal reciprocation by means of two levers 145 and 146. The lever 145 is pivoted to the stationary framework of the machine at 147. The lever 146 is fixed to a rock shaft 148 that is supported in the stationary framework. Rigid with the shaft 148 is a crank arm 149 having a roller stud that runs in the groove of a cam 150 fixed on the shaft 50 (see Fig. 9). 110 115 120

On the lower edge of the bar 144 is a hook 151 (Fig. 19). In the rotation of the cam 150 the hook 151 is moved into engagement 125 with the selected thread held by the yielding clamp member 78, and draws the thread across the needle 132 just rearwardly of the hook 152 of the needle. As the needle starts 130

- on its return stroke, the thread springs into the needle hook. In such return movement of the needle, the thread is drawn out from between the clamp members 78 and 79, and 5 is drawn in the form of a loop through the heddle eye that is held by the eye facer. A reed hook 153 (Figs. 3 and 8) is pivotally supported in the machine frame at 154 and is oscillated by means of an arm 155 10 fixed with relation to the hook and a rod 156 connecting said arm to an arm 157. The arm 157 is rigid with a sleeve 158 (Fig. 1) which is pivotally mounted upon the shaft 134. Rigid with the sleeve 158 is an arm 159 carrying a roller stud that lies in the cam groove 141. Near the end of its forward or thread-taking movement the reed hook 153 enters a pocket 160 in the block 142. This occurs after the needle 132 has drawn 20 a loop of thread into said pocket. Upon its inner or concave side the reed hook 153 is provided with a hook 161. As shown in Fig. 12, the hook 161 is located in a vertical plane at one side of the path of movement of the needle 132. As the reed hook is completing 25 its forward movement the point 162 of the reed hook enters the loop which has been drawn into the pocket by the needle 132, thereby spreading the two strands of the 30 loop as indicated in Figs. 12 and 13. The path of movement of the point of the hook 161 is slightly to the rear of the hook 152 of the needle. Consequently, as the reed hook is completing its forward stroke the hook 35 161 slightly distends the loop of thread. As soon as the point of the hook 161 has passed inside the loop, the loop springs back so that upon the ensuing retracting movement of the reed hook the hook 161 engages the loop 40 of thread and draws it off the hook 152 of the needle and through the reed. When the needle 132 is in its rearward position (as shown in Figs. 2 and 8) it is out 45 of the way when the harness and reed frame 21 is to be initially positioned, but the reed hook 153 is then in its forward position and consequently in the way of the leading bracket 24. The reed hook is therefore pivotally mounted with respect to the cam L⁸ 50 and the arm 155, and is releasably secured to the side of said cam by suitable means such as a spring plunger 163. When a new set of harness and reed is to be positioned at the mechanism, the spring plunger is 55 pulled out, thereby allowing the reed hook to swing back out of the way of the leading bracket 24 and the reed, the thread hook being afterward returned to operative relation to the proper space of the reed. 60 To hold the drawn-in threads temporarily there may be provided means similar to that described in Patent No. 1,115,399, said means including a wheel L¹¹ having radial plush-lined slots L¹² through which the reed hook 65 passes and through which it draws the warp

threads. The wheel L¹¹ is rotatably mounted in the machine frame and is rotated step by step by means including a yoke L¹⁰ pivoted at L¹⁹. The yoke L¹⁰ has a roller stud that lies in a cam L⁸ which is rigid with the arm 70 155. The yoke L¹⁰ has an arm L¹⁷ carrying a pawl L¹⁴ that engages a ratchet wheel L¹⁵ which is attached to the thread-holding wheel L¹¹.

The reed-feeding mechanism herein shown 75 is similar to that fully illustrated in Patent No. 1,115,399. The reed-feeding and opening plunger is actuated by means including crank arms M⁸ and M¹⁰ (Fig. 7) rigidly secured together, a link M¹¹ connecting the 80 arm M¹⁰ to an arm M¹² (Figs. 2 and 17), and a crank arm M¹³ rigid with the arm M¹². The arm M¹³ has a roller stud that lies in the cam groove D¹⁰ of a cam D⁹ fixed on the shaft 42. When the throw-out lever E¹³ 85 is operated, the movement of the arm E² on which the bell crank lever M¹² M¹³ is mounted causes the reed detent pawl (not herein shown) to be disengaged from the reed, as explained in said Patent No. 1,115,399. 90

Should the selector 61 fail to take a thread, it is desirable to stop the heddle-handling mechanism, the needle 132, the reed hook 153 and the reed feed while the selector mechanism continues to endeavor to take a thread. For this purpose, means has been provided for interrupting the application of power to the heddle-handling mechanism, the drawing needle, the reed hook and the reed feed without suspending the operation 100 of the thread-selecting and separating mechanism and the transfer device 144. It will be remembered that the thread-selecting and separating mechanism is actuated through the shaft 66, said shaft being driven from the drive shaft 50 through the gears 89 and 90, and that the transfer device 144 is actuated by the cam 150 on the drive shaft 50, whereas the heddle-handling mechanism, the needle, the reed hook and the reed feed are 110 actuated through the cam shaft 42, said cam shaft being driven from the drive shaft 50 through the clutch 53. In order, therefore, to suspend the action of the heddle-handling mechanism, the needle, the reed feed and the reed hook, I provide means for throwing out the clutch 53, said means being automatically operated upon the failure of the selector 61 to take a thread. This mechanism will now 120 be described.

The devices that sense the absence of a selected thread may be of any suitable character, as, for example, that fully disclosed in the Peterson patent hereinbefore mentioned, and therefore, it has been deemed unnecessary 125 to illustrate such mechanism in detail herein.

The arm 163 shown in Figs. 19 and 20 of the present drawings corresponds to the arm 159 of the Peterson patent. This arm is connected by means of a rod 164 to a crank 130

arm 165 having a hub which is splined to a shaft 166. Said hub is mounted in a bearing 167 which is attached to the slide 86. The shaft 166 is mounted in a bearing 168 carried by the stationary portion of the machine frame. Fixed to the shaft 166 is a crank arm 169 (Fig. 9) which is connected by means of a rod 170 to a crank arm 171 which is fixed with relation to the clutch-operating member 58. During the return movement of the separator plate 68, after a failure to take a thread, the arm 163 is swung downwardly, thereby causing the clutch-operating member 58 to be moved into position to disengage the clutch pin 55 from the clutch member 53.

The operation is as follows: Assuming that the heddle-positioning mechanism is in the separated or thrown-out position, the needle 132 in its rear position, the reed hook 153 swung back out of operative position, the slide 86 in its starting position, the reed detent hook in its elevated position, and the main carriage 1 in its starting position, namely, at the extreme right hand end of its range of movement. A pair of harnesses and a reed having been properly positioned in the harness and reed frame 21, said frame is placed in the main carriage 1. A warp having been clamped, stretched and deflected in the warp frame 10, the frame 10 is placed upon its supports 18 in the main carriage 1. The harnesses and the reed are then adjusted upon their supports into proper register with the devices that operate upon the harnesses and the reed, and the warp frame 10 is moved to bring the foremost thread into operative relation to the selector 61, the main carriage 1 being also moved if that be necessary to the proper positioning of the harnesses, reed and warp. The heddle-positioning mechanism is then thrown in, the reed hook secured to the cam L^s, the screw-threaded shoe 34 is placed in engagement with the feed screw 6, and the hand lever 125 operated to shift the belt to the tight pulley 51. As the selection of threads proceeds, the slide 86 is adjusted upon its guide 87 to the extent required by localized irregularities in the spacing of the threads and the difference between the widths of the warp and the harnesses. In any position of the slide 86 the transfer device 144 brings the selected thread to the needle 132. When the warp-drawing operation is completed the operator stops the machine, throws out the heddle-positioning mechanism, disconnects the reed hook from the cam L^s, disengages the member 34 from the feed screw 6, and moves the main carriage 1 as far as may be necessary to permit of the withdrawal of the harness and reed frame and the warp frame from the main carriage 1. The carriage 1 is then slid back to starting position to receive another warp frame and harness and reed

frame which have been loaded in the meantime.

Certain features of this invention are applicable to various types of machines for operating upon warps.

I claim as my invention:

1. A warp-drawing machine having, in combination, an operating mechanism, means for supporting the warp, means for supporting the harnesses, means for supporting the reed, means for causing relative traversing movement between the operating mechanism on the one hand and the several supporting means on the other, said movement being approximately proportionate to the sley of the harnesses, and means for adjusting the position of a portion of the operating mechanism with reference to the remainder of said operating mechanism to compensate for the difference in the width of the warp and the harnesses.

2. A machine for operating upon warps having, in combination, a reciprocatory drawing needle, a thread selector, a support for the thread selector, a warp support, means for causing relative traversing movement between the needle and the selector on the one hand and the warp on the other, and thread-controlled means for adjusting the position of the selector support toward the warp.

3. A machine for operating upon warps having, in combination, a supporting structure, a drawing needle on said structure, a support on said structure, a thread selector on said support, and means to adjust the position of said support on said structure in order to shift the field of operation of the selector relatively to the field of operation of the needle.

4. A machine for operating upon warps having, in combination, a supporting structure, a drawing needle on said structure, a support on said structure, a thread selector on said support, and thread-controlled means to adjust the position of said support on said structure.

5. A machine for operating upon warps having, in combination, a reciprocatory drawing needle, a thread selector, a support for the thread selector, and means for adjusting the position of said support relatively to the needle in order to shift the field of operation of the selector relatively to the field of operation of the needle.

6. A machine for operating upon warps having, in combination, a reciprocatory drawing needle, a thread selector, a support for the thread selector, and thread-controlled means for adjusting the position of said support relatively to the needle.

7. A machine for operating upon warps having, in combination, a warp support, a thread selector, a drawing needle, means controlled by the warp threads for adjust-

ing the position of the selector in order to shift the field of operation of the selector relatively to the field of operation of the needle, and means for placing selected 5 threads in position to be taken by the needle.

8. A machine for operating upon warps having, in combination, a thread selector, a warp support, means for causing relative traversing movement between the selector 10 and the warp support, and automatically-actuated means for further adjusting the position of the selector relatively to the warp.

9. A machine for operating upon warps having, in combination, means for holding a 15 series of warp threads; means for separating threads singly and successively from the series; means for feeding the warp-holding means across the path of movement of the separating means; and means bearing 20 against the foremost thread of the series for adjusting the position of the separating means.

10. A warp-replenishing machine having, in combination, means for supporting two 25 series of elements, said series being of unequal widths, means to select the elements of the narrow series, means to select the ele-

ments of the wider series, means to cause relative feed movement between the two series on the one hand and the two selecting 30 means on the other, said feed movement being approximately proportional to the sley of the narrow series, and means to adjust the position of the selecting means for the wider series to compensate for the difference in 35 the widths of the two series.

11. A warp-replenishing machine having, in combination, means for supporting two series of elements, said series being of unequal widths, means to select the elements of 40 the narrow series, means to select the elements of the wider series, means to cause relative feed movement between the two series on the one hand and the two selecting means on the other, said feed movement being approximately proportional to the sley 45 of one of the series, and means to adjust the selecting means for the other series to compensate for the difference in the widths of the two series.

In testimony whereof, I have hereunto set my hand.

HOWARD D. COLMAN.
